UNITED STATES PATENT OFFICE

CHARLES A. PRIEST, OF CHICAGO, ILLINOIS, ASSIGNOR TO THE SCHOLL MFG. CO. INC.,
OF CHICAGO, ILLINOIS, A CORPORATION OF NEW YORK

VIBRATOR AND METHOD OF USING THE SAME

Application filed November 23, 1927. Serial No. 235,334.

This invention relates to vibrators and the like and incorporates a new use for the same.

This invention relates more particularly to vibrators of the type actuated by a flexible drive shaft which in turn may be actuated by an electrical motor or equivalent means.

Devices of this character heretofore in use have been used extensively for facial massages and in various beauty or reducing treatments. However, I have found that a vibrator of the type set forth herein, if not essential, is at least highly desirable for the treatment of orthopedic disturbances and comparatively minor ailments of the human foot, such as corns, calluses, bunions, or the like.

A device of the type described herein, when applied to an afflicted portion of the human foot, tends to stimulate or produce circulation in the said portion, thereby materially aiding the blood, in carrying off the poisonous matter that usually accumulates in or adjacent to such afflicted portions. For instance, to effectively treat bunions wherein an oil collects and remains, it is necessary to provide circulation through the afflicted portion to thereby remove the collected oil. My invention when properly applied will frequently accomplish this result. However, in some instances in the treatment of certain ailments of the foot, it is desirable to use other instruments prior to the application of the vibrator and so it is desirable that the other instruments as well as the vibrator may be quickly and easily attached or connected to the same flexible shaft.

It is highly essential also in properly treating portions of the foot from which skin or the like, has been previously removed, that the applicator of the vibrator does not rotate but merely gyrates to adequately stimulate circulation in the afflicted portion without injuring the same.

Vibrators heretofore in use, for reasons that will become obvious hereinafter, have not been especially adapted to the proper treatment of corns, calluses, orthopedic disturbances of the foot and the like.

It is accordingly an object of the present

invention to provide a vibrator unit that may be easily and quickly attached and detached from a drive shaft.

Another object of the present invention is to provide a vibrator having a removable applicator associated therewith, which applicator is gyratory but not rotatable.

A further object of the present invention is to provide means adapted to be used in effecting a new method of treating ailments of a foot or similar extremity of a body.

Other and further important objects of the present invention will be apparent from the disclosures in the specification and the accompanying drawings.

This invention (in a preferred form) is illustrated in the drawings and hereinafter more fully described.

On the drawings:

Figure 1 is a fragmentary view in elevation of a flexible shaft secured to a clutch adapted to hold various instruments.

Figure 2 is a fragmentary view in elevation showing a vibrator unit embodying principles of the present invention in position for operative attachment to the end of a flexible shaft.

Figure 3 is a fragmentary plan view of the means for attaching the unit to a flexible shaft, said means being in separated position.

Figure 4 is a bottom plan sectional view taken substantially along line IV-IV of Figure 2.

As shown in the drawings:

In the illustrated embodiment of this invention there is shown a flexible shaft 1, the extremity of which is enclosed by a stiffened casing 2, the other extremity of the shaft being connected to and driven by an electric motor or equivalent means (not shown in the drawings). Secured to the outer end of the casing 2 is a sleeve 3 with means thereon for removably attaching an article thereto. As shown in Figure 1 a clutch 4 is attached to the sleeve 3. This clutch 4 is of the usual type of construction and adapted to receive various instruments such as drills, buffers, or the like, whereby the instruments will be actuated by the flexible shaft 1.

A novel vibrator unit has been provided to be also removably connected to the sleeve 3 for actuation by the drive shaft 1. This vibrator unit comprises a housing, generally indicated by the numeral 5, which includes a sleeve 6. The sleeve 6 is threaded at each end thereof, and at one end is expanded to increase both the inner and outer diameters adjacent the threaded portion 7. Also adjacent this threaded end 7, an integral shoulder 8 is provided to receive in abutment therewith a cap 9 apertured as at 10. Adjacent the other end of the sleeve 6, the bore therein is of a smaller diameter thereby providing an inner annular shoulder 11, and adjacent the extreme end of the sleeve, the outer diameter is reduced to accommodate a coupling sleeve 12.

Within the housing, sleeve 6, and the coupling sleeve 12, a shaft 13 is disposed. This shaft may be made of a single piece of material or, as shown, of two units secured together. An annular recess 14 is provided in the shaft 13 adjacent the junction point of the sleeves 6 and 12, to accommodate an inwardly projecting flange 15 on the sleeve 12, which flange abuts the end of the sleeve 6. The outer end of the shaft 13 is notched as at 16 to permit ready and effective engagement with the end of the drive shaft 1.

The means for coupling the vibrator unit to the drive shaft 1 include a lever 17 welded to a flat spring 18 secured to the sleeve 3 which tends to hold the forward end of the lever in abutment with the sleeve 3. The sleeve 12 is notched as at 19 to permit the same to embrace the rear portion of the spring 18, and a small notch 20 is also provided in the sleeve 12 to be engaged by a shoulder 21 adjacent the tip of the lever 17 to retain the respective parts in operative connection. The shoulder tip of the lever 17, of course, is manually raised to permit the sleeve 12 to slide thereunder, the shaft 16 engaging with the shaft 1 simultaneously therewith.

The inner end of the shaft 13 is provided with an enlarged portion 22 which is retained in place by the shoulder 11 within the sleeve 6. This portion 22 is recessed as at 23 to accommodate a substantially spheroidal tip 24 on the end of a gyratory shaft 25. Adjacent the spheroidal tip 24, the shaft 25 is tapered, as at 26, and at the other end of the tapered shaft, an enlarged arcuate and integral portion 27 is provided on the shaft 25 to substantially abut the cap 9, whereby the gyratory shaft is retained in operative connection with the rotatable shaft 13. It is to be noted that the recess 23 in the shaft 13, is offset to thereby provide an eccentric connection between the gyratory and rotatable shafts. When the shaft 13 rotates, the spheroidal tip 24 on the shaft 25 will follow the recess 23, the enlarged arcuate portion 27, will act as a pivot

for the gyratory shaft and the outer end 28 projecting through the aperture 10 in the cap 9, will oscillate through a universal plane but will not rotate. To further aid in retaining the arcuate portion 27 in its desired position, a collar 29 is provided within the end of the sleeve 6 and a projection 30 is provided on the arcuate portion 27 and is disposed between the cap 9 and the collar 29.

The projecting end 28 of the shaft 25 is inwardly threaded to accommodate an outwardly threaded shaft 31 secured to an applicator 32. The applicator 32 is retained in connection with the shaft 31 by means of a nut 33. By merely unscrewing the shaft 31 from the shaft 25, the applicator, of course, may be removed and replaced by another. The applicator shown in this instance is of a cup-like form and preferably, though not necessarily, made of a rubber composition. This form of applicator is found desirable in the massaging of foot ailments but obviously, if necessary, it may be replaced by an applicator of different configuration.

A substantially short sleeve 34 embraces the sleeve 6 adjacent the mid-portion or balance thereof and is secured thereto in any desired manner or as shown by a set screw 35. Pivotedly connected to a depending lug 36 on the sleeve 34 is a handle 37 which aids greatly in the proper application and manipulation of the vibrator unit, since the handle is attached at substantially the balance point of the device. The sleeve 34 and the handle 37 are angularly movable in relation to each other and may be clamped in any desired position of angularity by the tightening of the hand lever 38.

In the use of the present invention with relation to the remedying of foot troubles such as corns, calluses, and the like, a drill or buffer is first attached to the clutch 4 and the afflicted portion is drilled or buffed down. The clutch 4 is then removed from its connection with the drive shaft 1 and the vibrator unit is connected to the drive shaft. The afflicted portion of the foot is next thoroughly and effectively massaged with the applicator 32 or the like. It is to be noted as set forth hereinabove that the applicator will gyrate but will not rotate and thereby injure a patient.

From the foregoing it is apparent that I have provided an improved vibrator unit which is readily attachable to or detachable from a drive shaft and which is adapted to be used with a new and effective method of treating orthopedic disturbances and ailments of the foot.

I am aware that many changes may be made and numerous details of construction may be varied through a wide range without departing from the principles of this invention and I, therefore, do not purpose limiting

the patent granted hereon otherwise than necessitated by the prior art.

I claim as my invention:

A massaging device including a massaging implement, a handle therefor including a sleeve having an aperture in the wall thereof, and having a slot formed in one end thereof, a shaft journaled for rotation in said sleeve and operatively connected to the massaging implement, a second sleeve having a shaft rotatable therein and arranged to slide into the first sleeve so that its shaft locks into the shaft in the first sleeve, means for removably coupling the two sleeves, the said means including a member on the second sleeve arranged to enter the slot in the first sleeve, and having a reversely bent spring member with a toe arranged to enter the aperture in the wall of the first sleeve.

20 In testimony whereof I have hereunto subscribed my name at Chicago, Cook County, Illinois.

CHARLES A. PRIEST.
